[57] CLAIM

The ornamental design for a “voice recognition adapter”, as shown and described.

DESCRIPTION

FIG. 1 is a top plan view of the voice recognition adapter in accordance with my new design;

FIG. 2 is a front elevation view thereof;

FIG. 3 is a rear elevational view thereof;

FIG. 4 is a right side elevation view thereof, the left side being substantially identical thereto;

FIG. 5 is a bottom plan view thereof;

FIG. 6 is a top right front perspective view thereof; and,

FIG. 7 is a bottom right rear perspective view thereof.
